Des. 207,409
Patented Apr. 11, 1967

207,409

LAZY SUSAN OR THE LIKE

Clayton A. Laughlin, Minneapolis, Minn., assignor to Arthur Salm, Inc., Chicago, Ill., a corporation of Illinois

Filed May 2, 1966, Ser. No. 2,129

Term of patent 14 years

(Cl. D44—10)

FIG. 3

FIG. 1 is a perspective view of a lazy susan incorporating my new design;

FIG. 2 is a top plan view thereof;

FIG. 3 is a front elevational view thereof;

FIG. 4 is a side elevational view thereof; and

FIG. 5 is a perspective view of one tray of the lazy susan of FIG. 1.

The essential features of my design are shown in full lines on the drawing.

I claim:

The ornamental design for a lazy susan or the like, substantially as shown and described.
